(57) **CLAIM**

The ornamental design for an electrical connector, as shown and described.

DESCRIPTION

FIG. 1 is a top plan view of an electrical connector showing my new design;

FIG. 2 is a bottom plan view thereof;

FIG. 3 is a top front perspective view thereof;

FIG. 4 is a bottom rear perspective view thereof;

FIG. 5 is a left side elevation view thereof;

FIG. 6 is a right side elevation view thereof; and,

FIG. 7 is another front perspective view thereof.

The broken line illustration in the figure drawings is included to show unclaimed subject matter only and forms no part of the claimed design.
